UNITED STATES PATENT OFFICE.

FRANK L. SESSIONS, OF COLUMBUS, OHIO, ASSIGNEE TO THE JEFFREY MANUFACTURING COMPANY, A CORPORATION OF OHIO.

MINING-MACHINE.

1,132,800.

Specification of Letters Patent. Patented Mar. 23, 1915.

Application filed September 3, 1910. Serial No. 560,416.

To all whom it may concern:

Be it known that I, FRANK L. SESSIONS, a citizen of the United States, residing at Columbus, in the county of Franklin and 5 State of Ohio, have invented certain new and useful Improvements in Mining-Machines, of which the following is a specification, reference being had therein to the accompanying drawing.

10 This invention relates to mining machines of the breast type in which there is a main frame held stationary during each cutting action and a cutter frame permanently mounted on the stationary frame but relatively movable with respect thereto to advance its cutters into the coal.

The principal object of the invention is to provide an improved means for effecting the movement of the carriage or cutter frame with respect to the main or stationary frame.

Stated more specifically, the object is to provide a carriage feeding mechanism comprising ropes, or their equivalents, for transmitting the power from one frame to the other. It has been heretofore proposed to make use of ropes for this purpose, but so far as I am aware the earlier proposals have contemplated the use of only a single strand 25 of rope, usually located at one side of the center of the carriage. When such a single strand of rope was used it applied the moving force eccentrically of the carriage with the result that there was a strong tendency 30 of the carriage to be turned as well as move longitudinally, thus causing a binding or cramping action on the guides. By my invention I pass the rope over suitable guide sheaves and carry it backward so that 35 it acts upon the carriage at two separated points substantially symmetrically disposed with respect to the longitudinal axis. With this improved construction the forces are balanced at the opposite sides of the carriage with the result that there is no tendency 40 for binding or cramping at the guides. Preferably, the winding mechanism for the rope is mounted on the carriage so as to be driven by the same motor which drives the 45 cutting mechanism. Preferably, also, I provide two rope mechanisms, one for advancing the carriage and the other for retract-

ing it, the two mechanisms being similar to each other.

A further object of the invention is to 55 provide means whereby one of the same ropes which is used for moving the carriage on the frame can also be used for moving the whole machine bodily from point to point about a mine.

60 Other objects of the invention will be apparent from the following description and claims.

In the drawings—Figure 1 is a plan view 65 of a mining machine constructed in accordance with my invention. Fig. 2 is a side elevation of the same. Fig. 3 is a vertical cross section of the machine along the line 3—3 of Fig. 1, the clutch operating levers being removed. Fig. 4 is a longitudinal 70 section of the rear part of the machine along the lines 4—4 of Figs. 1 and 5, the motor being shown in side elevation. Fig. 5 is an enlarged plan view of one end of the machine.

75 The stationary frame of the mining machine consists of the horizontal runner bars 1^a, 1^b, the U-shaped cross bars 1^b, 1^b connecting the runner bars, the upper horizontal bars 1^a, 1^b, supported by and secured to the upper ends of the cross bars 1^b, and the upper cross bars 1^a, 1^b, one of which spans each end of the stationary frame. Vertical stud shafts 2^a, 3^a, 4^a and 5^a are mounted one at 80 each corner of this stationary frame and on 85 these shafts rotate the idler sheaves 2, 3, 4 and 5.

The grooves 6^a formed on the inner faces 90 of the bars 1^a, receive the outer edges of the frame plate 6 which constitutes the sliding carriage. The cutter head 7 which is secured to the front end of the carriage, is equipped with the usual endless cutter chain 7^a and is guided at its forward end by the hanger 7^b which depends from the front 95 cross bar 1^a and in which reciprocates the central frame element 7^c of the cutter head.

The electric motor 8 is secured to the carriage frame 6. This motor drives the cutter chain through a train of power transmitting 100 gearing comprising the armature bevel pinion 9, the intermeshing bevel gear 10, the vertical shaft 11 on which gear 10 is keyed, the clutch collar 12 splined on shaft 11, the

pinion 15 sleeved on shaft 11 and provided with clutch teeth mating with clutch element 16, spur wheel 17 meshing with pinion 15 and sprocket wheel 19 fast on the hub extension of gear wheel 17 and about which passes the cutter chain.

The vertical shaft 11 revolves in bearings 12 and 13, the latter a boss in the carriage plate 6, and the former formed in the yoke 11^a, which is supported by vertical legs or uprights 6^b bolted to the rear end of plate 6. A ball bearing 14 interposed between the base of gear 10 and the bearing 13 affords a step bearing for the shaft. The clutch element 16 is shifted vertically into and out of engagement by a lever controlled yoke. The gear 17 revolves on a stud shaft 18 fixed to the plate 6 which depends from and is rigidly connected to the carriage 20 plate 6. The plate 6 is adjustably fastened to the rear end of the cutter head 7 by means of the usual take up connecting device 6^c.

The carriage and cutter head are fed forward driving the chain into the coal and the same parts are withdrawn from the coal after the kerf is cut by the power of the motor applied by means of ropes and winding mechanisms therefor. Two sets of gearing, both driven by the motor, are utilized to operate two feed ropes, one to feed the carriage forward and the other to pull it back. The pull back gearing is arranged to operate its winding drum at a greater speed than the forward feeding gearing. The sets of gearing are driven from the worm 29 which is fast upon the shaft 11. The worm engages the worm wheel 21 keyed on the shaft 22, which latter is supported by bearings 23, 24 formed on the uprights 6^b. The spur pinion 25 and spur gear 26 keyed on the shaft 22 mesh with corresponding gear 27 and pinion 28, respectively, both of which are freely mounted on a cross shaft 29 supported in bearings 30, 31, 32 and 33 arranged on rear upper extensions 11^b of the yoke 11^a. The gear 27 and pinion 28 are adapted to engage with jaw clutches 34 and 35, respectively, controlled by shifting levers 36 and 37, respectively, connected to the operating handle 38 by the link 39 in such manner that only one of the clutches may be in engagement at a time. It will be seen that by this arrangement the shaft 29 may be driven from the motor through the bevel gears, worm gears and spur gears at two speeds according to which of the clutches 34 or 35 are in engagement.

Keyed to the cross shaft 29 are two worms 66 and 67 each provided with a ball bearing thrust collar 68 and 69 and engaging with worm wheels 40 and 41 respectively keyed to vertical shafts 42 and 43. Shaft 42 turns in bearings 44, 45 and 46 formed on suitable

extensions of the uprights 6^b, yoke 11^a, and the plate 6. Shaft 43 turns in three similar bearings 47, 48 and 49. The rope drums 50 and 51 are loosely mounted on vertical shafts 42 and 43 respectively, and are adapted to be rotatably connected thereto by multiple disk friction clutches 50' and 51'. In each of these clutches, one set of disks is keyed to the drum and the other set to the shaft. Pressure is applied to the clutches 76 by rotating cam levers 52 and 53 operating cams 52' and 53', the levers working in opposite directions and being joined by a link 54 which prevents both clutches being applied at the same time.

The ropes 55 and 56 terminating in hooks 57 and 58 are wound on the two drums respectively.

The operation is as follows: The machine being placed in proximity to the coal and the frame 1 secured in the manner common to mining machines, the rope 56 is drawn out from the drum 51 and passed around the idler sheaves 2 and 3 and the hook 58 is attached to the eye 58' secured at the extreme edge of the carriage 6 opposite drum 51. The rope 55 is drawn out from the drum 50, passed around the idler sheaves 4 and 5 and the hook 57 attached to the eye 57' secured at the extreme opposite edge of the carriage 6. The clutch 35 being put in engagement with the gear 27 causes the shaft 29 to revolve at its slow speed; the lever 52 is then moved to apply the friction clutch within the drum 51 causing the rope 56 to be wound up, feeding the carriage 6 and with it the cutter head 7 toward the coal. When the cut is finished the lever 52 is released, the clutch 35 disengaged, the clutch 34 engaged causing the shaft 29 to revolve at its rapid speed, the lever 52 moved to apply the friction clutch within the drum 50 causing the rope 55 to be wound pulling the carriage 6 and cutter head 7 back quickly. The inactive rope in each case is pulled off its idle rotating drum. These feed ropes may be used for handling the machine by disengaging the hooks from the carriage and, after passing the ropes around the appropriate levers, 115 hooking them to suitable placed rock posts. It will be noticed that the machine will then be moved at double the speed of carriage feed or pull back due to the fact that in carriage feed and pull back the levers are attached to the carriage which is a moving and not a stationary anchor. It will of course be understood that both ropes are not used at the same time for moving the machine bodily. The operator can use 125 whichever rope will most conveniently give the required movement.

An important advantage of the arrangement of ropes shown is that the carriage will be pulled in each direction squarely 130

from both sides, preventing cramping, each rope extending in parallel lines along the two sides of the machine, its two ends being attached to the carriage at the two opposite 5 sides thereof.

What I claim is:—

1. In a mining machine, the combination of a stationary frame, a carriage guided for movement with respect to the frame along 10 fixed straight lines, a motor, a winding drum driven by the motor, a rope extending longitudinally at one side of the machine and having one end wound on the drum and the other end secured at the opposite 15 side of the machine, and two transversely separated sheaves over which the rope is guided between its ends, the said guides causing the rope when wound to draw longitudinally upon the carriage at two points 20 substantially equidistant from the longitudinal axis of the carriage.

2. In a mining machine, the combination of a stationary frame, a carriage guided for movement with respect to the frame along 25 fixed straight lines, a motor on the carriage, a winding drum on the carriage driven by the motor, a rope extending longitudinally from the carriage at one side thereof and having one end wound on the drum and the 30 other end secured to the carriage at the opposite side thereof, and two transversely separated sheaves on the frame over which the rope is guided between its ends, the said guides causing the rope when wound to draw longitudinally upon the carriage at two points 35 substantially equidistant from the longitudinal axis of the carriage.

3. In a mining machine, the combination of a stationary frame, a carriage guided for 40 movement with respect to the frame along fixed straight lines, a motor on the carriage, a winding drum on the carriage driven by the motor, a rope extending longitudinally from the carriage at one side thereof and 45 connected to the drum to be wound thereon, rope-guiding devices mounted on the main frame and symmetrically disposed with respect to the longitudinal axis of the carriage, and means for connecting the other 50 or free end of the rope to the carriage at the side opposite to that from which it initially extends whereby the rope applies a longitudinal moving force to the carriage at two 55 points substantially equidistant from the longitudinal axis thereof.

4. In a mining machine, the combination of a stationary frame, a carriage guided for movement with respect to the frame along 60 fixed straight lines, a motor on the carriage, a winding mechanism mounted on the carriage and connected to be driven by the motor, a rope engaging the said winding mechanism, rope-guiding and securing devices arranged to hold the rope in position 65 along two parallel lines substantially equi-

distant from the longitudinal axis of the carriage, whereby the rope when wound serves to apply two equal advancing forces to the carriage on opposite sides of the longitudinal axis thereof, a second winding 70 mechanism mounted on the carriage and also connected to be driven by the motor, a second rope engaging the said second winding mechanism, and other rope-guiding and securing devices arranged to hold the 75 second rope in position along two parallel lines equidistant from the longitudinal axis of the carriage, whereby the rope when wound serves to apply two equal retracting forces to the carriage on opposite sides of 80 the longitudinal axis thereof.

5. In a mining machine, the combination of a stationary frame, a carriage guided for movement with respect to the frame along fixed straight lines, a motor, two symmetrically disposed drums on opposite sides of the carriage, means for optionally connecting one or the other of said drums with the motor, guide pulleys upon the stationary frame, a rope wound upon one drum and 85 extending over a guide pulley at one end of the frame to a point of attachment at the opposite side of the carriage from its drum, and a second rope wound upon the other drum and extending over a guide pulley at 90 the other end of the frame to a point of attachment at the opposite side of the carriage from its drum.

6. In a mining machine, the combination of a stationary frame, a carriage guided for 100 movement with respect to the frame along fixed straight lines, two winding drums symmetrically disposed at opposite sides of the carriage, guide pulleys on the stationary frame, a rope wound upon one drum and extending over a guide pulley at one end of the frame to a point of attachment on the side of the carriage opposite to its drum, a second rope wound upon the other drum and 105 extending over a guide pulley at the other end to a point of attachment on the side of the carriage opposite to its drum, a motor, gearing between the motor and the drums, the said gearing being adapted to rotate the drum which acts to retract the carriage 110 faster than the drum which acts to feed the carriage forward, and means for breaking the power connection between the motor and either of the drums, substantially as set forth.

7. In a mining machine, the combination of a stationary frame, a carriage movable relative thereto, two symmetrically disposed winding drums on the carriage, a rope adapted to be wound upon one drum to advance the carriage relative to the frame, a rope adapted to be wound upon the other drum to retract the carriage, a transverse shaft, gearing between each drum and the shaft, the said gearing comprising friction 115

clutches, and means whereby one clutch is disengaged when the other is disengaged, a motor, and a change speed gearing between the motor and the shaft, substantially as set forth.

8. In a mining machine, the combination of a stationary frame, a movable carriage, two winding drums mounted on the carriage, a rope adapted to be wound upon one drum to draw the carriage forward, a rope adapted to be wound upon the other drum to retract the carriage, a shaft between the two drums, gearing between each drum and the shaft comprising a friction clutch and a worm, the said gearing tending to rotate each drum in a direction to wind the rope, means whereby one of the said friction clutches is maintained inoperative when the other is operative, a motor, and connections between the motor and the said shaft.

9. In a mining machine, the combination of a stationary frame, a movable carriage with cutting mechanism, means for guiding the carriage in a straight horizontal path fixed with respect to the frame, a motor on the carriage, means for advancing the carriage on the frame comprising a winding drum mounted on one side of the carriage and driven by the motor, a rope secured to the winding drum, and guide means on the front end of the frame, the rope being passed over said guide means and back to the carriage to which it is secured at the side opposite the side on which the winding drum is mounted, and means for retracting the carriage and thereby unwinding the rope from the drum.

10. In a mining machine, the combination

of a normally stationary frame, a carriage movable with respect to the frame, a motor on the carriage, a rope drum on the carriage connected to be driven by the motor, a rope connected at one end to the drum to be wound thereon, a guide on the frame over which the rope can pass, and means for detachably connecting the rope at the other or free end to the carriage for moving it with respect to the frame, the rope, when its free end is detached from the carriage, being adapted to be passed laterally to a point of anchorage external to the machine for moving the machine bodily.

11. In a mining machine, the combination of a normally stationary frame, a carriage movable with respect to the frame, a motor on the carriage, a rope drum on the carriage connected to be driven by the motor, a sheave on the main frame mounted for rotation about a vertical axis, a rope connected at one end to the drum to be wound thereon and adapted to pass over the said sheave, and means for detachably connecting the other or free end of the rope to the carriage to move it with respect to the frame, the rope being adapted, when its free end is detached from the carriage, to be passed laterally over the said sheave to a point of anchorage external to the machine for moving the machine bodily.

In testimony whereof I affix my signature, in presence of two witnesses.

FRANK L. SESSIONS.
